PORTABLE RECEPTACLE AND FRAME
THEREFORJacob Schoenfeld, New York, N. Y., assignor to
United Carr Fastener Corporation, Cambridge,
Mass., a corporation of Massachusetts

Application July 23, 1932, Serial No. 624,227

4 Claims. (Cl. 150—29)

This invention relates to portable receptacles.

One object of the invention is to provide a portable receptacle having frame elements so crossed as to be opened by pressure thereon, said frame members being in improved association between certain walls of the receptacle so that the pressure is exerted through said walls with the latter acting as a cushioning means for said elements.

10 Another object of the invention is the provision of a portable receptacle having a plurality of frame elements provided with improved spaced means for resilient interengagement, one of said means being superior to the other so that an opening movement at the superior means causes opening movement of the other means as well.

Another object of the invention is to furnish a plurality of improved frame members having bars of equal length and a plurality of sets of 20 crossed arms connected to the ends of the bars, the arms of one frame member being so bent as to be resiliently engageable by portions of the other arms in relative proximity to said bars.

Another object of the invention is to provide 25 a frame structure with pivoted crossed arms and locking or catch means in improved association with said arms.

A further object of the invention is the provision of a device of the type mentioned having 30 few and simple parts and which is inexpensive to manufacture and assemble, neat in appearance, durable, reliable, convenient in operation, and efficient in use.

Other objects of the invention will become 35 apparent as the specification proceeds.

With the aforesaid and other objects in view, the invention consists in the novel combinations and arrangements of parts hereinafter described in their preferred embodiments, 40 pointed out in the subjoined claims, and illustrated on the annexed drawing, wherein like parts are designated by the same reference characters throughout the several views.

In the drawing:

45 Figure 1 is a view in end elevation of a device embodying the invention.

Fig. 2 is a view in side elevation of a frame embodying the invention and showing the bag in dot dash lines.

50 Fig. 3 is a horizontal sectional view taken on the broken line 3—3 of Fig. 2.

Fig. 4 is a view in end elevation showing the device in open position.

55 Fig. 5 is a fragmentary top plan view of the device in open position.

Fig. 6 is a fragmentary view in end elevation of a modification of the device.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

Generally described, this invention provides any portable receptacle such as a handbag or the like and a novel frame having improved association therewith. Said frame may include U shaped frame members, the levers or arms of which are pivotally interconnected and cross each other so that pressure on the arms causes the 20

frame members to move apart and open the bag. Any suitable catches or locking means may coact with said arms to prevent the opening movement. Said bag may be made of a tough heavy body material and may include side walls and end gussets of concave form within which said arms may be disposed so that multiply thicknesses of the heavy material are available through which the pressure can be exerted on said arms or locking means for opening the bag. Where the side 30

walls and gussets have reinforcing seams, the latter prevent distortion or curling of the walls due to repeated pressure exerted thereon for moving the arms. A novel catch means may be associated with frame members of different constructions, and being characterized in that a plurality of resilient spaced catch means are provided, one of which is superior in holding power to the other so that any opening movement for the superior catch means is communicated to the 40

other to cause the bag to open throughout, but such opening movement being insufficient for this purpose if exerted on the catch means having the lesser power. The frame members may also include rigid bars and the arms being resilient, 45

for snap or recessed resilient engagement with each other to hold the bag releasably closed, the arms being connected to registering points of the bars, and certain of the arms being offset for said engagement.

50 Referring in detail to the drawing, 10 denotes a device embodying the invention. The same may include a plurality of frame members 11, 12 arranged for movement toward and away from each other. Each frame member may be of U-

55

shaped form, having an upper rigid bar or channel 13, the bars of the different frame members being arranged to lie side by side in a plane and being preferably equal in length. The frame member 11 may have a plurality of depending levers or arms 14 and the frame member 12 may have corresponding arms 15. These arms may be secured at the upper ends at registering points of the frame members, as at the ends 16 thereof as shown. The arms 15 may extend along planes, which may be at right angles to bar 13, and the arms 14 being offset toward each other as at 17 so as to lie between the arms 15 and across the same as at 18. It will be noted that the portions 19 of said arms above 18 lie in the same corresponding planes and side by side, while the arm portions below 18 are in different planes. Moreover, each arm may have an angular portion 20 at the region 18, said arms being thence downwardly extended at a relatively small divergent angle, and their lower portions 21 being bowed together and movably or pivotally interconnected at 22.

Alignment of the end portions of the frame members 11, 12 at 16 is assured by the multipoint engagement between the arms 14, 15 at 18 and 22. While the frame members are being moved apart, the arms are in constant sliding engagement with each other, and even when fully open, as in Fig. 4, there is sufficient engagement at 21 to hold the frame members in proper relation. Such engagement can be increased by gradually increasing the width of said arms and hence the sliding surface from the upper to the lower portions of said arms.

For releasably interengaging the frame members, various means may be provided, such as locking devices located on bars 11, 12 according to the conventional practice, but it is a feature of this invention that such devices are unnecessary, and that the bars 11, 12 may be perfectly uniform, although ornamental devices may be affixed thereto. Moreover, this invention provides what is in the nature of a concealed locking means since the manner of opening the bag is not readily apparent, and particularly so, since the arms 14, 15 can be concealed in the receptacle. Preferably the interengaging means is of such a nature as to release due to pressure on the arms. Thus I may provide one set of said arms, such as the arms 15, with catch means, as, for instance, the recessed portions 23, 24 at 18, so arranged as to releasably engage the adjacent crossing portions of the arms 14, said arms resiliently interengaging at said recesses. If desired, the recesses 23 may be deeper than those at 24 to afford a superior holding engagement at 23. If now pressure is exerted on the arms 14, 15 at the right hand end of the frame, the engagement at 24 will be released but that at 23 will continue. But by exerting the pressure at the left hand end of the frame, the engagement at 23 is released and sufficient force is transmitted through the rigid bars 13 to cause the engagement at 24 to open. If a rapid or strong force is applied at the right hand end of the frame, the engagement at both 23 and 24 may be opened, but this can be prevented by a sufficient depth of the recess 23, and in fact the general operation as above described will be sufficient for all practical purposes. It may also be noted that the depth of recess 23 may be made sufficient to require that a twist be given to the adjacent arms in a counterclockwise direction for releasing the engagement. It will be appreciated that the recesses shown are in-

tended as a simplified illustration of one embodiment of the invention.

If desired, the arms 14, 15 may be arranged as shown at 14a, 15a and provided with a positive locking means in addition to the resilient catch means, the former to be used at such times as especially reliable closure is required. Such positive locking means may act directly between the arms, and one form thereof may include a finger 25 pivotally connected at 26 to the arm 15a and lying substantially in the plane of arm 14a, said finger having preferably a right angle end recess, one wall 27 of said recess forming a shoe for abutting the finger 14a, and the other wall of said recess forming a thin guide extension 28 overlying said arm. A portion of said finger at the shoe may be frusto conical to afford sufficient bearing surface. The finger is reliably held in the position shown by the resilience of said arms. If the use of this positive lock is not desired, the finger may be swung downward out of the way of the arms, and may be held relatively stationary by frictional engagement at the pivot. If desired, the arms 14a, 15a may be downwardly extended as shown at 29, whereby levers are formed, although these terms are used herein as equivalents to arms. The extensions 29 may constitute finger piece portions for manipulating the arms, and the latter may then be arranged in any required proximity to each other. While the extensions 29 may be arranged in cross relation, they are preferably extended laterally so that pressure exerted thereon will tend to cause the arms to move apart with the bars 13 moving toward each other. This arrangement will tend to prevent accidental opening of the handbag by pressure, as when the handbag is carried between the arm and the body of the person. But when pressure is exerted on the arms above the pivot 22, the device will open.

The device 10 may include a bag 30 that may be of conventional character, but the same having novel and improved cooperation with the frame as hereinafter described in detail. Said bag may consist of leather, composition material, textile fabric, or the like, and may have a suitable lining of textile or other feasible material, if desired. Thus the bag 30 may have side walls 31, 32 interconnected at the bottom as by an integral fold portion 33 and secured at the top in any suitable manner to the bars 13. Also interconnecting said side walls, end gussets 34 of any well known character, are provided, these gussets being concave and having suitable folds for expansion. The walls 31, 32 and the gussets may have linings 35, 36, and the gussets may be interconnected with the side walls by reinforcing seams. The latter may be formed, for example, by inturning the material of the walls, gussets and linings at their edge portions as shown at 37 and stitching the same through as at 38.

The elements of the frame structure, such as 14, 15, and 14a, 15a may be disposed between the multiply, heavy body walls 31, 32 thus provided, and are preferably arranged within the concave spaces afforded by the gussets. Due to the concavity of the latter, the side wall portions of the gussets supplement the adjacent portions of the walls 31, 32 to afford a cushioning and distributing means through which pressure can be exerted and transmitted to the arms as indicated by arrows 39. The cushioning action may be increased by the linings. Hence the operator need not exert the pressure directly upon the relatively thin arms such as 14, 15 nor upon 75

finger pieces such as 29, but conveniently grasps a side edge portion of the handbag and comfortably presses thereon.

Due to the heavy body multi-ply character of the pressure transmitting wall portions, the same will not be creased or marred by pressure against said arms or other parts. And since the arms are in relative proximity to the reenforcing seams at 37, the edge portions of the handbag will not be distorted or curled by repeated pressure. Moreover, the maximum space is afforded within the handbag, since by this arrangement the said arms are positioned in relative proximity to the ends of the receptacle.

15 It will be appreciated that various changes and modifications may be made in the device as shown in the drawing, and that the same is submitted in an illustrative and not in a limiting sense, the scope of the invention being defined in 20 the following claims.

I claim:

1. A handbag frame including a plurality of frame members movable toward and away from each other, each of said frame members having a 25 bar and a plurality of depending arms secured thereto, the arms of the different frame members being pivotally interconnected at their lower ends and crossing each other in different positions of the frame members with said bars close together 30 and remote from each other, the arms of one frame member being between the arms of the other frame member, the different arms slidably engaging each other in course of said movement, and the arms increasing in the width of their sliding surfaces from their upper to their lower ends.

2. A frame for handbags including a plurality of frame members having portions movable toward and away from each other, each of said frame members having an arm, the arms of the 40 different frame members being swingably interconnected and crossing each other above the point of interconnection so that pressure on the arms for moving the same toward each other causes said portions to move apart, said arms having below the point of interconnection extensions

spaced with respect to each other so that pressure on said extensions for moving the same toward each other causes the arms to tend to move apart and said portions to move together, whereby accidental movement of the frame members and opening of the handbag by pressure at the general region of the sides of the handbag is prevented except as said pressure is confined to said arms. 5

3. A holder having a frame and front and back cover portions and gussets located therebetween, 10 said frame comprising, in combination, two U-shaped frame members each having a connecting portion and side portions and pivotally connected at the ends of the side portions thereof, said side portions crossing each other between the pivoted 15 ends and the connecting portions, and releasable engagement means located intermediate the ends of the side portions to provide means to hold the holder in closed position, said front and back cover portions attached to the said connecting portions, 20 said gussets attached to said front and back cover portions in spaced relation to and between said side portions, said front and back cover portions adapted to overlie and conceal said side portions when viewed from the front, back or bottom of 25 the holder but exposed to view at the ends of the holder, said side portions being normally removed from the front, back and bottom portions of the holder in both open and closed positions of said frame members. 30

4. A frame for a container of the class described comprising a pair of complementary U-shaped frame members each formed from a single piece of material having a top bar portion and a depending arm at each end of the top bar, 35 the arms of adjacent ends of said frame members being pivoted together to permit relative movement of the crossbars toward and away from each other, said adjacent arms crossing each other between the pivoted ends and the bar members, said two bar portions being of equal length and some of said arms being bent adjacent to their points of connection with the bar members so that said top bars may have their ends opposite each other. 40

JACOB SCHOENFELD. 45
